UNITED STATES PATENT OFFICE.

JOHN OBRIG, OF NEWARK, NEW JERSEY, ASSIGNOR TO A. J. HEDGES & CO.,
OF NEW YORK, N. Y.

DESIGN FOR A METAL SLIDE FOR WEARING-APPAREL.

SPECIFICATION forming part of Design No. 25,351, dated April 7, 1896.

Application filed August 29, 1894. Serial No. 521,643. Term of patent 7 years.

To all whom it may concern:

Be it known that I, JOHN OBRIG, a citizen of the United States, residing at Newark, in the county of Essex and State of New Jersey, have invented and produced an original Design for a Metallic Mounting for Wearing-Apparel, of which the following is a specification.

The accompanying drawing shows a front or face elevation of a mounting exhibiting the new design.

The reference-letter C designates the mounting as a whole. The general shape of the mounting C is triangular or three sided. As shown, there is a triangular exterior boundary-line. At the exterior boundary there is a plain triangular border a with rounded corners b. Included within this exterior triangular boundary is an interior circular boundary-line c. The space between

the interior circular boundary-line c and the exterior triangular border is occupied with ornamental scrollwork f, as shown.

The distinguishing characteristic of the design is the triangular exterior contour associated with the interior circular boundary-line and the scrollwork between the triangular exterior contour and the interior circular boundary-line, as shown.

I claim as my invention—

The design for a metallic mounting for wearing-apparel, substantially as herein shown and described.

In witness whereof I have hereunto signed my name in the presence of two subscribing witnesses.

JOHN OBRIG.
